UNITED STATES PATENT OFFICE.

JOSEPH HINKS, OF BIRMINGHAM, COUNTY OF WARWICK, ENGLAND.

LAMP.

SPECIFICATION forming part of Letters Patent No. 274,326, dated March 20, 1883.

Application filed January 16, 1883. (No model.) Patented in England May 13, 1882, No. 2,265, and in Belgium December 20, 1882.

To all whom it may concern:

Be it known that I, JOSEPH HINKS, a subject of the Queen of Great Britain, and a resident of Birmingham, in the county of Warwick, England, manufacturer, have invented certain new and useful Improvements in Lamps for Burning Light or Volatile Oils, (for which I have received Letters Patent in Great Britain, No. 2,265, dated May 13, 1882, and in Belgium, 5 dated December 20, 1882, and have made application for German patent, dated December 14, 1882, and for Austro-Hungarian patent, dated December 21, 1882,) of which the following is a specification.

15 My invention has for its object to facilitate the trimming of the wicks and the lighting of the said lamps and the filling of the reservoirs of the said lamps; and my said invention consists of the construction and arrangements 20 hereinafter described, and illustrated in the accompanying drawings, of the parts of the said lamps, whereby the gallery carrying the chimney and globe and dome or deflector of the lamp can be raised for trimming the wicks and 25 for lighting the lamp without the removal of the chimney and globe from the gallery, and the burner raised so as to expose the open mouth of the reservoir for filling the same with oil without separating or detaching any 30 parts of the lamp.

Figure 1 represents in vertical section a portion of a lamp containing one of the arrangements of my invention, and Figs. 2 and 3 represent elevations of a part of the same. In 35 Fig. 1 the burner and gallery are represented raised and the oil-reservoir open for filling.

The same letters indicate the same parts in Figs. 1, 2, and 3.

A is the oil-reservoir. B is the metallic 40 mount or collar, cemented to the mouth of the oil-reservoir. C is the gallery, carrying the chimney and globe and the dome or deflector. D is the burner, capable of a rising-and-falling motion from and to the mount B. To the under 45 side of the fixed mount B are two vertical guide-tubes, E E, connected together at bottom by the ring E². On the under side of the gallery C are two metallic rods, F F, capable of sliding in the fixed guide-tubes E E. The 50 burner D is also provided with tubes D² D², which slide upon the rods F F of the gallery.

On opposite sides of one of the rods F are two notches, G and G², and each of the rods F is provided near its upper end with a shallow depression, K, with which depressions the spring-tongues L L, made from the burner-tubes D² D², can engage. H is a horizontal bolt carried by the mount B and pressed outward by the spring I, so as to cause it to engage with or snap into one or other of the two notches G G² 55 in one of the rods F when the said notches are brought opposite the bolt, so as to fix the gallery either in its lowered position or raised position. By pressing inward the spring-bolt H its inner acting end is withdrawn from the 60 notch in the rod F with which it is engaged, and the gallery C is released and may be raised or lowered. The burner D is not fixed permanently to the mount B, but is capable of being raised from and depressed upon the mount. 65 When in its depressed position the burner D is temporarily fixed to the mount B by the rotating ring M at the lower part of the burner, fastened in its place by the hooks and studs at N P. (See Figs. 2 and 3.) 70

When it is required to gain access to the wicks for trimming them or for lighting the lamp the gallery C is released by pressing inward the spring-bolt H, and the gallery C is then pressed upward with a little force into the position 75 shown in Fig. 1, the rods F F sliding in the guide-tubes E E, in which position it is fastened by the snapping of the bolt H into the notch G² in the rod F. After trimming the 80 wicks or lighting the lamp the bolt H is pressed inward. The gallery C is thereby released and may be lowered to the burner, the spring-bolt H, when the gallery has reached its lowered position, snapping into the upper notch, G, in the rod F, and fixing the said gallery. 85

When it is desired to fill the oil-reservoir A the burner D is first unfastened by turning the ring M, and the spring-bolt H is pressed inward. The burner D and gallery C are now raised together into the positions represented 90 in Fig. 1, the gallery being fixed in its raised position by the bolt H snapping into the bottom notch, G², and the burner being fixed to the gallery C and supported in its raised position by the tongues L L falling into the depressions K K in the rods F F, as seen in the 95 said Fig. 1. The open mouth of the oil-reser- 100

voir A is now exposed, and oil may be poured into it, the surface of the oil being visible.

The gallery C and burner D may be removed from the oil-reservoir for cleaning or repair or for introducing new wicks by unfastening the ring M, and pressing inward the bolt H and lifting bodily the parts C and D from the oil-reservoir.

Figs. 4 and 5 represent vertical sections of another arrangement of my invention. Fig. 6 is a plan of upper side of the mount fixed on the oil-reservoir. Fig. 7 is a side elevation of the gallery, and Fig. 8 is a side elevation of the burner. The same letters indicate the same parts in Figs. 4, 5, 6, 7, and 8. In this arrangement the gallery C is provided with three rods, F G H, and the burner D with a fourth rod, I, the said rods F, G, H, and I sliding in the guide-tubes E E on the fixed mount B. The opposite rods, F G, on the gallery C are each furnished with a spring-bolt, F² G², and the third rod, H, also with a spring-bolt, H². (See Fig. 6.) The rod I on the burner D is also furnished with a spring-bolt, I². (See Fig. 6.) The rods F G on the gallery C have upper and lower shoulders, K K L L, with inclines in opposite directions made upon them for retaining, in conjunction with the spring-bolts F² G², the gallery C in its raised and lowered positions. The third rod, H, on the gallery is furnished with a shoulder, M, without an incline, near its lower end, which shoulder acts only as a stop for preventing the complete withdrawal of the gallery from the lamp excepting when the spring-bolt H² is released. The rod I on the burner D has a notch at N. This notch N, in conjunction with the bolt I², is for the purpose of supporting the burner D in its raised position. When the gallery C and burner D are in their lowered or normal positions the gallery C is fastened in that position by the spring-bolts F² G² engaging under the top shoulders, K K, on the rods F G. As the gallery C cannot rise, the burner D is consequently fixed down between it and the mount B.

In order to raise the gallery C for trimming the wicks or lighting the lamp, the spring-bolts F² G² are simultaneously pressed inward, so as to release the rods F G. The gallery C can now be raised into the position represented in Figs. 4 and 5, where it is supported and fixed by the spring-bolts F² G² snapping under the bottom shoulders, L L, on the rods F G, the upward range of motion of the said rods F G, and consequently of the gallery, being limited by the bolt H² engaging with the stop-shoulder M on the third rod, H, carried by the gallery.

When it is wished to gain access to the oil-reservoir A, for filling it, the gallery C, together with the burner D and rod I, is raised into the position represented in Fig. 5, in which position the bolts F² G² snap under the shoulders L L on the rods F G, and the bolt I² engages with the notch N in the rod I and supports and fixes the gallery and burner in their raised positions.

In order to lower the gallery, or the gallery

and burner, it is necessary to press inward the spring-bolts F² G², so as to release the two rods F and G, the said rods F G, on the complete depression of the gallery, or gallery and burner, being refastened by the snapping of the said bolts upon the upper shoulders, K K. To remove the gallery and burner from the lamp, for renewing the wicks or for cleaning, after the burner has been brought to the position Fig. 5, it is only necessary to press inward the third spring-bolt, H², thereby releasing the stop-rod H, when the burner and gallery can be removed.

I am aware that a sliding gallery has been used, but I lay no claim to a sliding gallery excepting in the respects hereinafter pointed out.

Having now described the nature of my invention, and the manner in which the same is to be performed, I wish it to be understood that I claim as my invention of improvements in lamps for burning light or volatile oils—

1. The combination, with the body of the lamp, of the sliding burner and sliding gallery, substantially as described.

2. The combination, with the body of the lamp, of the vertically-sliding gallery and the burner, also capable of sliding with said gallery, the latter being movable independently of the former, substantially as described.

3. The combination of the gallery, rods connected therewith, fixed guide-tubes, in which said rods move, and the catches or bolts for fastening said gallery in its raised or lowered position, substantially as described.

4. In a lamp, the combination of the gallery, the burner detachably connected therewith, the rods and guide-tubes, and catches or fastening devices, substantially as described, for fastening the gallery in its raised or lowered position, and for fastening the burner in its lowered position and supporting it in its raised position, as set forth.

5. In a lamp, the combination of the gallery, its rods and guide-tubes therefor, the burner, its rod and guide-tube, and the spring bolts or catches, having shoulders or notches, as explained, with which said bolts or catches engage, whereby the gallery and burner may be fastened in either a raised or lowered position or removed entirely from the lamp, substantially as described.

6. In a lamp, the combination of the sliding gallery and burner, rods having shoulders at their upper and lower ends, spring-catches which engage said shoulders and fasten said sliding parts in either a raised or lowered position, another rod connected with said gallery and shouldered at its lower end, and a spring catch or bolt which engages said last-named shoulder when said sliding parts are raised and prevents their being lifted too far, substantially as described.

JOSEPH HINKS.
